PRACTICE TYPEWRITER

Amy Emanuel, Asheville, N. C.

Application January 27, 1943, Serial No. 473,709

3 Claims. (Cl. 35—5)

This invention relates to new and useful improvements in practice typewriters, and has for its principal object the provision of a novel practice instrument which affords the student many of the benefits of practice on an actual typewriter, and has the additional advantage of teaching the student greater accuracy than would be the case if the practice were done on the actual machine.

Another object of the present invention is to provide a practice machine of the character described which is formed with a full-sized keyboard of conventional or any other desired arrangement, and wherein the individual keys have an action which closely simulates the key action on a standard typewriter.

A further object of the invention is the provision of an apparatus of the character described which is simple and inexpensive to construct, particularly in that the entire machine may be formed almost entirely of wood without employing any critical materials of any character whatsoever.

The machine of the present invention is light in weight and, being also compact in construction, is accordingly readily carried around by the student, thus permitting practice at odd times, which periods might otherwise be wasted.

Yet another object of the invention is to provide a practice typewriter of the character described which employs a novel and inexpensive spring arrangement for returning the keys, when depressed, to normal position. These spring elements, as are the other parts of the device, are formed from wood or other similar material, and are so arranged as to be readily replaced when they become broken or worn through use.

The present invention is illustrated in the drawings as applied to a typewriter only, although it will be appreciated that the principles are equally applicable to other writing machines, such as shorthand machines and calculating machines.

In the drawings:

Fig. 1 is a perspective view of one embodiment of the present invention, a portion of the housing being broken away to show the interior arrangement.

Fig. 2 is a top plan view of the main body portion of the device.

Fig. 3 is a plan view of the same with the upper wall removed.

Fig. 4 is a transverse vertical section taken on line 4—4 of Fig. 2.

Fig. 5 is a broken vertical section taken on line 5—5 of Fig. 4.

Fig. 6 is a broken section taken through a modified form of spring supporting means.

Fig. 7 is a broken plan view of the structure shown in Fig. 6.

Fig. 8 is a broken vertical section taken on line 8—8 of Fig. 6.

Fig. 9 is a broken transverse vertical section taken through another form of spring supporting means.

Fig. 10 is a broken section taken through a modified form of the present invention.

Fig. 11 is a bottom plan view of the mechanism shown in Fig. 10.

The practice machine of the present invention is preferably, though not necessarily, contained within a housing comprising a main body portion 10 and a hinged cover portion 11. In virtually all typewriters, the several rows of keys are on descending planes in the direction of the operator, and in order to conform to this arrangement the end walls 13 of the main body section, which supports and houses the mechanism, are of decreasing depth in the direction of the operator. The lower section 10 is provided with an inclined upper wall 14 which may be formed from a flat sheet of wood or other suitable material, and may be suitably supported on the interior of the lower section to permit its forward edge 15 to be plane with the upper edge of the front wall 16 of the section, and its rearward edge 17 to be plane with the upper edge of the rear wall 18 thereof. This upper wall is preferably made removable from the lower section 10 of the housing.

The depressible keys are shown as comprising shanks 21 which are journaled for vertical, longitudinal movement in apertures 22 formed in upper wall 14, heads 23 suitably secured to the upper terminals of shanks 21, and headed pins 24 at the lower end of the shanks which prevent removal of the keys from their supporting apertures. The arrangement of the keys may correspond generally to any standard keyboard arrangement, and in the instance shown four rows of keys are illustrated. Although the upper wall 14 is downwardly inclined, the upper surface is preferably formed with a plurality of spaced, longitudinal, substantially horizontal surfaces 25, one for each row of keys, and one at the lower or front end of the wall for an elongated simulated spacer bar 26 which is similarly supported by a plurality of shanks 21.

The following means are provided for maintaining the keys in elevated position and for instantaneously returning them to such position after they have been manually depressed and then released. An internal block 30 is seated on lower wall 31 of the body section 10, the upper surface of the block being formed in a stepped arrangement providing a supporting surface 32 for each row of flat spring elements 23, which are supported at one end thereof in a recess 34 with a snug fit. The forward edge of each surface 32 may be bevelled, as shown at 35, to permit flexing of the spring, as shown in the in-

termide row in Fig. 4. These spring elements are desirably made from flat strips of wood, although they may also be formed from plastic material, metal, or any other available flat, springy material. All of the spring elements 33 are so disposed in the housing as to cause the outer end of each element to be engaged on its upper surface by the lower headed portion 24 of the key, as shown in Fig. 3.

Figs. 6, 7 and 8 show an alternative method of mounting the flat springs. In this instance, each row may include a strip 40 having a flat upper surface 41 for the spring 42, the inner terminal of which is received in a square, milled slot 43, and the several slots are closed by a continuous strip 44 extending the full length of the housing. In this instance, also, the spring 42 may be secured in the supporting apertures by a force or friction fit, from which apertures they may be quickly removed when they become broken. They may, if desired, be further secured by a small quantity of glue, and in Fig. 9 the strip 48 provides no supporting aperture for the spring 49, the latter merely being secured on the upper surface 50 by glue 51. In the arrangement shown in both Figs. 6 and 9, strips 40 and 48, respectively, may be mounted on blocks 53 and 54, which may likewise have a stepped surface, or the entire block may be formed in one piece.

By virtue of the arrangement shown in Figs. 1 to 9, inclusive, it will be seen that when upper wall 14 of the lower housing section 10 is removed, all of the flat spring elements are visible and readily accessible for installation or repair. This is a considerable advantage, since any repairs may be effected by the student without the necessity of taking the apparatus to a repair shop.

In the modified arrangement shown in Figs. 10 and 11, the block 60 is carried by upper wall 61. In this case, the lower surface of the block is formed with a ridged portion 62 for the flat springs 63, and a milled slot 59 may be used, a strip 64 closing the slots. Aligned apertures 65 and 66 pass through upper wall 61 and block 60 which support shank 67. A modified stop means comprising a pin 68 passing through an aperture 69 adjacent to the lower end of shank 67 is illustrated here. Downward movement is limited by head 70 at the upper end of the shank. In some instances, this pin arrangement may also be employed to limit downward movement of the shank. In this arrangement, when it is desired to inspect or repair the spring means, the entire upper wall 61, together with block 60, may be withdrawn from the lower housing section 10. In some instances it may be desirable to eliminate the lower wall 31 of the housing, particularly in cases wherein the embodiment of the invention is not designed for portability.

In Fig. 2, no specific characters are shown on the upper surfaces of the keys for the reason that the particular selection of characters is a matter of choice. The arrangement of keys may, however, conform generally to a standard typewriter, which includes the letters of the alphabet, the numerals, various symbols, and other necessary keys. The figures in the drawings are not, of course, drawn to any particular scale, since in the case of a typewriter the dimensions may be those of a portable typewriter or a full-sized machine.

What I claim is:

1. A practice typewriter or the like formed of wood or similar inexpensive material and comprising a housing including an upper wall having a plurality of rows of spaced apertures therein, a plurality of simulated depressible keys including head portions, shank portions journaled within such apertures for vertical movement, and foot portions, said head and foot portions being of greater diameter than that of the shank portions, thus limiting downward and upward movement, respectively, of said depressible keys, each adjacent row of keys being of increased height to simulate a typewriter keyboard, means for normally retaining the keys in elevated position and for returning such keys to elevated position after they have been manually depressed and released, such means comprising a flat spring formed of wood for each key, one end of such spring yieldingly engaging the lower terminal of the key, and means for rigidly supporting the opposite end comprising a block formed with rows of recesses for receiving such opposite terminals of the spring, the block further being formed with supporting surfaces for a portion of the length of each spring.

2. A practice typewriter or the like comprising a housing including a removable upper wall having a plurality of rows of spaced apertures therein, a plurality of simulated depressible keys including head portions, and shank portions journaled within such apertures for vertical movement, each adjacent row of keys being of increased height to simulate a typewriter keyboard, means for normally retaining the keys in elevated position and for returning such keys to elevated position after they have been manually depressed and released, such means comprising a flat wooden spring for each key, one end of such spring yieldingly engaging the lower terminal of the key, and means for rigidly supporting the opposite end comprising a block formed with rows of apertures for receiving such opposite terminals of the spring, said springs being readily removable from said apertures to permit replacement when the same become worn.

3. A practice typewriter or the like formed entirely of wood and comprising a housing formed with an inclined upper wall which is removable from the housing, and having a plurality of rows of spaced apertures therein, a plurality of depressible keys, each comprising a headed shank positioned in an aperture and being journaled therein for longitudinal movement, means for limiting the upward movement of said keys, and resilient means for normally retaining such keys in an elevated position and for returning the keys to such elevated position after they have been manually depressed and then released, such means comprising a plurality of flexible, flat spring elements, means for supporting such elements at their inner terminals in fixed position, the opposite terminals being free and engaging the lower terminals of the shanks, such supporting means comprising a block having a plurality of recesses therein for receiving such inner terminals, and an elongated strip closing such recesses and forming apertures for supporting such terminals with a friction fit.

AMY EMANUEL.
